US0D1028901S

(12) **United States Design Patent** (10) **Patent No.:** **US D1,028,901 S**
(45) **Date of Patent:** **** May 28, 2024**

(54) **ELECTRICAL CONNECTOR ASSEMBLY**

(71) Applicant: **Shenzhen Aukeyhi Technology Co., Ltd.**, Shenzhen (CN)

(72) Inventor: **Yang Wang**, Guangdong (CN)

(73) Assignee: **HULKMANN INNOVATION TECHNOLOGY (SHENZHEN) CO., LTD.**, Shenzhen (CN)

(**) Term: **15 Years**

(21) Appl. No.: **35/516,219**

(22) Filed: **Aug. 8, 2022**

(80) **Hague Agreement Data**

Int. Filing Date: **Aug. 8, 2022**

Int. Reg. No.: **DM/222900**

Int. Reg. Date: **Aug. 8, 2022**

Int. Reg. Pub. Date: **Feb. 10, 2023**

(30) **Foreign Application Priority Data**

Jul. 28, 2022 (CN) 202230486846.6

(51) **LOC (14) Cl.** **13-03**

(52) **U.S. Cl.**

USPC **D13/133; D13/149**

(58) **Field of Classification Search**

USPC D13/120, 133, 137.4, 145–146, 149; D14/225; D23/262

(57) **CLAIM**

The ornamental design for an electrical connector assembly, as shown and described.

DESCRIPTION

1. Electrical connector assembly

1.1: Perspective

1.2: Perspective

1.3: Front

1.4: Back

1.5: Left

1.6: Right

1.7: Top

1.8: Bottom

1.9: Perspective

1.10: Perspective

1.11: Front

1.12: Back

1.13: Left

1.14: Right

1.15: Top

1.16: Bottom

1.17: Perspective

(Continued)

The broken lines in the figures are for the purpose of illustrating portions of the article that form no part of the claimed design.

1 Claim, 17 Drawing Sheets

(58) Field of Classification Search

CPC G02B 6/3893; H01R 13/642; H01R 43/24;
H05B 41/285

See application file for complete search history.
